UNITED STATES PATENT OFFICE.

SAMUEL STEWART, OF LEWISTON, MAINE, AND OSCAR L. OWEN, OF WHITINSVILLE, MASSACHUSETTS, ASSIGNORS TO WHITIN MACHINE WORKS, OF WHITINSVILLE, MASSACHUSETTS, A CORPORATION OF MASSACHUSETTS.

YARN-WINDING MACHINE.

Application filed March 26, 1923. Serial No. 627,619.

To all whom it may concern:

Be it known that we, SAMUEL STEWART, of Lewiston, in the county of Androscoggin and State of Maine, and OSCAR L. OWEN, of Whitinsville, county of Worcester and Commonwealth of Massachusetts, have invented certain new and useful Improvements in Yarn-Winding Machines, of which the following, taken in connection with the accompanying drawings, is a specification.

Our invention relates to machines for winding yarn from a package upon a quill or bobbin, and especially to the devices employed to guide and control the yarn; and it consists in certain novel features of construction, arrangements and combination of parts, which will be readily understood by reference to the description of the drawings, and to the claims to be hereinafter given.

Reference is to be had to the accompanying drawings forming part hereof, wherein: Figure 1 is a front view of the driving end of a winding machine embodying my invention; Figure 2 an end elevation thereof; Figure 3 is a sectional elevation on line 3—3 of Figure 1; Figure 4 is a partial plan view of Figure 1; Figure 5 is an enlarged sectional elevation of the driving means of the tables, supporting the supply package; Figure 6 is an axial section of the yarn tension and Figure 7 is a perspective view of the yarn guide and traverse rail.

Like reference characters refer to like parts in the several views of the drawings.

The winding machine in construction comprises spaced apart end frames 1 (only the head end being shown in drawings) and one or more intermediate supports 2, all rigidly connected by the upper rails 3 and lower rails 4 on each side of the machine. The lower rails 4 serve as supports for a plurality of winding members or spindles 5 for supporting the receiving bobbins 6. Rotary motion is imparted to the winding spindles 5 from the driving cylinder 7 by the bands 8. The packages 9, containing the supply of yarn to be rewound on bobbins 6, are supported on rotating tables 10, the packages 9 being maintained on the centre of the tables 10 by the skewers 11 (Figure 5) projecting loosely into the central bores of the packages. The skewer 11 is in a fixed relation with the centre of journal 12 of the rotary table 10. The journal is preferably formed integral

with the stand 13 supported by the rails 3.

Although different means may be used for imparting rotary motion to the package tables we prefer to make use of a friction drive comprising the leather faced pulleys 14 in frictional contact with the peripheries 15 of the package tables 10. The pulleys 14 are loosely mounted on the revolving shafts 15. The hub of the pulleys 14 is provided with a radial slot 30 as shown in dotted lines in Figure 5. Collar 16 in fixed relation with the shaft 15 is provided with a lug 31 loosely engaging with the slot 30, thus transmitting the rotary motion of the shaft 15 to the friction pulley 14. A compression spring 17 encircles the hub of the pulley, one end of which abuts against the web of pulley and the other against the face of the collar 16, thus maintaining the pulley 14 and package table 10 in proper frictional relation with each other. Rotary motion is imparted to the shafts 15 by a suitable train of gears driven from the shaft 18 which receives its motion through another train of gears from the driving shaft 19 of the machine.

In operation the yarn 20 contained on the supply packages 9 is drawn over the fixed guide rods 21 located centrally above the supply packages, thence the yarn is drawn through the tension device 22, of common construction, and guide eye 27 and wound onto the receiving bobbin 6. The rotary speed of the supply package is very small as compared with that of the receiving bobbin on the winding spindle, being just sufficient to slowly unwind the yarn from the package thus preventing entanglement and consequent breakage.

The tension devices 22, one for each strand of yarn, are fixed to the shafts 23 slowly revolving in bearings supported by brackets 24 fixed to uprights 25 on top of the machine. Motion is imparted to shaft 23 from shaft 18 by suitable transmitting means. The rotary motion of the tension reduces the strain on the yarn while it is being wound onto the receiving bobbin.

The winding of the yarn onto the receiving bobbin is effected by the rotation of the spindle supporting the bobbin drawing the yarn from its supply package over the guide rod 21 through the tension 22 and guide eye 27 and then wound on the receiving bobbin 6. The guide eye 27 is fastened to a rail or

bar 26 which has a reciprocating motion actuated by the bobbin builder motion common to spinning and twisting machines.

We claim:

- 5 1. In a yarn winding machine having a plurality of winding members, rotatable tables supporting the supply packages, friction pulleys coacting with the peripheries of said tables to rotate them, revolving shafts 20 located beneath the rotary tables, said friction pulleys being loosely mounted thereon, collars fixed to said shaft in clutching connection with the hubs of the friction pulleys, compression springs between the collars and 25 the pulleys, yarn guiding rods located above the supply packages, yarn tensioning means and reciprocating rails with guides thereon to guide the yarn onto the bobbins.
- 10 2. In a yarn winding machine having a plurality of winding members, rotatable centrally located beneath the rotary tables, said friction pulleys being loosely mounted thereon, collars fixed to said shafts cooperating with the hubs of the friction pulleys, and compression springs between the collars and the pulleys.
- 15 2. In a yarn winding machine having a plurality of winding members, rotatable

tables supporting the supply packages, friction pulleys coacting with the peripheries of said tables to rotate them, revolving shafts 20 located beneath the rotary tables, said friction pulleys being loosely mounted thereon, collars fixed to said shaft in clutching connection with the hubs of the friction pulleys, compression springs between the collars and 25 the pulleys, yarn guiding rods located above the supply packages, yarn tensioning means and reciprocating rails with guides thereon to guide the yarn onto the bobbins.

In testimony whereof, we have signed this 20 specification.

SAMUEL STEWART.
OSCAR L. OWEN.
